UNITED STATES PATENT OFFICE.

CHARLES J. HENSCHEL, OF BROOKLYN, NEW YORK.

SHIP'S TELEGRAPH.

1,393,684.

Specification of Letters Patent. Patented Oct. 11, 1921.

Application filed April 4, 1919. Serial No. 287,437.

To all whom it may concern:

Be it known that I, CHARLES J. HENSCHEL, a citizen of the United States, residing at Brooklyn, county of Kings, and State of New York, have invented certain new and useful Improvements in Ships' Telegraphs, of which the following is a full, clear, and concise description.

My invention relates to ships' telegraphs, that is, to signaling devices used upon shipboard for enabling an officer located for the time being upon one part of the vessel to transmit certain conventional signals to another officer or attendant located upon a different part of the vessel, and to receive from him an affirmative indication that the signal is understood.

More particularly stated, my invention relates to the type of ship's telegraph which as usually built comprises two instruments known respectively in this art as a transmitter and receiver, yet each having to some extent at least the functions of both a transmitter and a receiver, the two instruments being connected together by means of flexible connections of great length extending between them, the energy required for transmission being furnished altogether by the muscular efforts of the respective operators.

The main purpose of my invention is to provide two instruments with a single set of flexible connections extending therebetween and common thereto, the various parts being so adapted and arranged that this set of flexible connections may be at one moment under control of the one instrument and at a different moment under control of the other instrument, and while under control of one instrument being incapable of causing that instrument to register an indication, but capable of causing the other instrument to register an indication.

A further purpose of my invention is to prevent confusion in the transmission and reception of signals, by so forming and arranging the parts that the operator at the transmitting station must finish his signal and lock his instrument before the operator at the receiving station can effectively make any response.

My invention also comprehends general improvements in the mechanism of the ship's

telegraph, for the purpose of increasing the general efficiency thereof.

Reference is made to the accompanying drawings forming a part of this specification, and in which like reference characters indicate like parts throughout the several figures.

Figure 1 is a front view of the transmitter and the supporting column upon which it is mounted, the transmitter except for the addition of the supporting column having a structure like that of the receiver.

Fig. 2 is a substantially central vertical section through the mechanism shown in Fig. 1.

Fig. 3 is a section on the line 3—3 of Fig. 2, looking in the direction indicated by the arrows.

Fig. 4 is a fragmentary section corresponding to the right hand portion of Fig. 2, but showing the device as adapted for use with flexible shafting instead of with a chain drive.

Fig. 5 is a diagrammatic elevation of my system as used with a chain drive.

Fig. 6 is a diagrammatic elevation of my system as employed with a flexible shafting drive.

Mounted upon the top of a supporting column 7 is a casing 8, provided with a face plate 9 and serving as a housing.

The face plate is provided with legends Back, Ahead, Stop, Full, Half, Slow, the three legends last mentioned each being duplicated.

The face plate 9 is at its outer or peripheral edge provided with notches 10, spaced equidistant and serving as sector notches.

An arm 11, carrying a handle 12, is provided with a collar 13, secured firmly upon the adjacent end of a tubular shaft 14.

Extending through the tubular shaft 14 is a smaller shaft 15, provided with a swivel head 16. A swivel fork 17 engages the swivel head 16, and therewith forms a swivel joint.

A lever 18, having approximate V-form, is journaled upon the arm 11 by aid of bearings 19, and is adapted to swing slightly in relation to the arm 11, as may be understood from Fig. 2. When the lever occupies its position indicated by dotted lines, it is in its

normal condition of inactivity. When it occupies its position indicated by full lines, it is in its abnormal condition—as when the arm 11 is being moved, or at least is 5 unlocked and ready to be shifted. The dotted arrows in Fig. 2 indicate the direction of movement of the lever 18 as it returns to its normal position after each time it is used.

10 The lever 18 carries a pawl 21, the point of which is so formed and arranged as to easily slip into some one of the notches 10 and thus for the time being lock the arm 11 so as to prevent it from being shifted.

15 The tubular shaft 14 extends through another tubular shaft 22, and fitted rigidly upon this tubular shaft is a disk 23, having a portion 24 projecting radially outward and serving as a pointer.

20 The tubular shaft 22 is supported by bearings 25 and 26. The bearing 25 is integral with the face plate 9, and the bearing 26 is carried by a spider 27. This spider has the general form indicated in Fig. 3, and is provided with feet 28 secured to the casing.

25 Mounted rigidly upon the tubular shaft 22 is a centering wheel 29, provided with a number of notches 30, spaced equidistant, as shown in Figs. 2 and 3. Engaging the 30 centering wheel is a roller 31, carried by an arm 32, and adapted to fit into the notches one at a time as the centering wheel is turned. The arm 32 is mounted upon a pin 33, and thus adapted to rock. The pin 33 is supported by a lug 34. A spring 35 encircles the pin 33 and engages the arm 32 so as to press it against the centering wheel 29.

The arm 32 carries a clapper 36, supported upon a wire stem 37. Disposed adjacent the 40 clapper 36 is a gong 38, so arranged that the rocking of the arm 32 causes the clapper to strike the gong. A stem 39 supports the gong and is mounted upon a lug 40.

The centering wheel performs two offices. 45 First, it enables the operator to stop the arm 11 in certain definite and exact positions, corresponding to and indicated by the legends displayed by the face plate. Second, it causes the clapper to strike the gong.

50 A bearing 41, having the form of a sleeve, extends from the spider 27, and abuts against a bearing 42, extending inwardly from the face plate 9. Mounted within these two bearings 41, 42, and supported thereby, is 55 a shaft 43. Encircling this shaft 43, and slidably relatively thereto, is a sleeve 44, carrying a gear wheel 45 and swivel head 46. The sleeve 44 engages a spline key 47 which extends through it and is carried by the shaft 43.

60 A sprocket wheel 48 is mounted rigidly upon the shaft 43, and carries a sprocket chain 49.

65 A forked lever 50 is journaled to rock on a pin 51, and is provided with a slot 52,

through which extends a pin 53, carried by the small shaft 15. Mounted rigidly upon the shaft 15 is a collar 54, and engaging this collar is a spring 57. Both the collar and the spring are located within a compartment 70 56 with which the tubular shaft 14 is provided.

The tubular shaft 14 carries a gear wheel 58, and the tubular shaft 22 carries a gear wheel 59, these two gear wheels each having 75 the same number of teeth, which are beveled. The two gear wheels also have each the same diameter.

Each time the lever 18 is rocked relatively to the arm 11, as indicated by dotted lines 80 in Fig. 2 and as above described, the small shaft 15 is moved endwise relatively to the tubular bearing 14, through which it extends. As a consequence, the fork 50 is rocked upon the pin 51, so that the sleeve 85 44 is moved a little distance along the shaft 43. The gear wheel 45 moves out of mesh with the gear wheel 58 and into mesh with the gear wheel 59 each time the lever 18 swings from its position indicated by full 90 lines to that indicated by dotted lines in Fig. 2. This movement is under impulse of the spring 57. Each time the lever 18 is moved into the position indicated in Fig. 2 by full lines however, the gear wheel 45 95 moves out of mesh with the gear wheel 59 and into mesh with the gear wheel 58.

Thus with the handle 20 pressed toward the handle 12 as shown in Fig. 2, if the arm 11 be rocked, the gear wheel 58 must cause 100 the gear wheel 45 to turn and to drive the shaft 43 with its sprocket 48. Yet with the handle 20 moved away from the handle 12, the pawl 21 thus entering one of the notches 10 and the lever 18 appearing as indicated in 105 dotted lines in Fig. 2, the arm 11 can make no movement, and any movement of the chain 49 now causes the sprocket wheel 48 to turn the shaft 43 so that the gear wheel 45 turns the gear wheel 48, thus causing 110 the tubular shaft 22 to turn the pointer 24 and register an indication.

The chain 49 extends through a slot 61, and is provided with a number of wire links 49^a and turn buckles 49^b. The chain engages 115 a number of guide pulleys 62, as may be understood from Fig. 4.

Fig. 4 shows the transmitter and receiver with the chain extending therebetween. The transmitter is at the left of the figure, the receiver appearing at the right. As a matter of convenience the parts of the receiver corresponding to the parts 10, 18, 20, and 24 of the transmitter are designated as 10^a, 18^a, 20^a, and 24^a.

120 A movement communicated to the chain by means of the transmitter mechanism is readily transmitted to the receiver, and there communicated to such movable parts as may 125 for the moment be under control of the 130

chain. Similarly a movement communicated to the chain by the receiver mechanism is readily communicated to such movable parts, within the transmitting mechanism, as may 5 now be under control of the chain.

Referring more particularly to Fig. 2, it will be noted that when the lever 18 is pressed toward the arm 11 as shown by full lines, and the arm 11 is then rocked as else- 10 where described, the gear wheel 58 turns the gear wheel 45 so that the chain 49 is driven by movements of the arm 11, while the gear wheel 59 is idle and the pointer 24 is for the time being motionless. When, however, the 15 arm 11 occupies its normal position indicated by dotted lines, so that the arm 11 is locked by the pawl 21 and the disengagement of the gear wheel 45 from the gear wheel 58 frees the chain 49, any movement conferred 20 upon the chain from the receiving station must turn the sprocket wheel 48, shaft 43 and gear wheels 45 and 59, and hence the pointer 24 is turned accordingly.

Thus the operator at the transmitting station can register an indication at the receiving station but not at the transmitting station, and the operator at the receiving station can register an indication at the transmitting station but not at the receiving 30 station.

Only one operator can use the apparatus at a time. As a result the operator at the receiving station is unable to answer any signal until the latter is finished and the 35 operator at the transmitting station has locked the arm 11.

Instead of the chain 49, I sometimes use a line of shafting, as shown in Figs. 5 and 6. This line of shafting contains shaft sections 40 63, 63^a, 63^b, bevel gears 63^c, a universal joint 63^d, and an extensible coupling 63^e. The line of shafting is therefore essentially a flexible shaft.

In order to adapt my apparatus for use 45 with a flexible shaft, I find it convenient to use at each of the two stations the arrangement shown in Fig. 6.

The shaft section 63 extends through bearings 64, 65, carried by hangers 66, 67, the 50 same extending from a spider 68 and the latter having feet 69 which are secured to the casing. The spider 68 is provided with a bearing 70, having the form of a sleeve, and through which the shaft 43 extends. This 55 shaft carries a bevel gear 71, which meshes with a bevel gear 72 carried by the shaft section 63. A set collar 73 rests upon the bearing 65 and sustains the end thrust of the shaft section 63.

60 The other parts shown in Fig. 6 are as to structure and action identical with those already described in connection with Fig. 2.

The operation of my device is as follows: The various parts being assembled and

arranged as shown in the drawing and as 65 above described, the device is ready for use.

Suppose the apparatus is in the condition indicated in Fig. 4 or in Fig. 5, and that the operator at the transmitting station wishes to transmit the signal indicated by the 70 legends Back and Slow. He grasps the handle 12 (see Fig. 2) and with it the handle 20, thus rocking the lever 18 slightly in a clockwise direction according to Fig. 2, as 75 above described. This moves the pawl 21 out of engagement with the face plate 9 and leaves the arm 11 free. The operator then rocks this arm slightly in a contra-clockwise direction according to Fig. 4, so that the legend Slow is displayed through the V- 80 shaped arm 18, the handle 20 being released and the point of the pawl being allowed to enter the proper notch 10. This locks the arm 18.

The movement just described for the arm 85 18 causes the gear wheel 45 to move out of engagement with the gear wheel 59, into engagement with the gear wheel 58 and then back into engagement with the gear wheel 59. The movement of the arm 11, 90 taking place as it does while the gear wheel 45 momentarily in engagement with the gear wheel 58 and out of engagement with the gear wheel 59, causes the gear wheel 45 to turn the shaft 43 and move the chain or 95 flexible shaft, but has no effect whatever upon the tubular shaft 22 or the pointer 24 at the transmitting station.

At the receiving station, however, the situation is different, the lever 18^a remaining stationary and the pointer 24^a moving in response to the signal thus transmitted.

The operator at the receiving station, hearing his gong sounded, glances at the receiver and notes the signal as indicated 100 by the pointer. As soon as the pointer stops moving, he answers by merely repeating the signal, which causes the pointer 24 at the transmitting station to move to the position associated with the signal in question. The 105 gong at the transmitting station is of course, sounded along with the movement of the pointer, and the operator at the transmitting station is apprised that his signal is understood, and just how it is understood.

The ship's telegraph now remains undisturbed until another signal is to be transmitted, whereupon the cycle of operations is repeated.

I do not limit myself to the particular 120 mechanism shown, as variations may be made therefrom without departing from my invention, which is commensurate with my claims.

I claim:

1. In a ship's telegraph the combination of 125 a set of flexible connections extending from one station to another and movable from

each of said stations for the purpose of transmitting signals, an actuating device at each station for moving said set of flexible connections in order to transmit a signal, an 5 indicating member at each station to be actuated by said set of flexible connections in order to receive a signal, and mechanism located at each station and controllable at the will of the operator for connecting said set 10 of flexible connections with either said actuating device or said indicating device at the will of the operator and of locking said actuating device in order to render it inactive while said set of flexible connections is connected with said indicating member.

15 2. In a ship's telegraph the combination of a single set of flexible connections extending from one station to another for the purpose of transmitting signals, an actuating 20 member at each station and operable by the muscular energy of the operator for moving said set of flexible connections, a driven member located at each station and adapted to be moved by said set of flexible connections in 25 order to register an indication, mechanism located at each station and controllable at the will of the operator for connecting said set of flexible connections with said driven member and disconnecting the same therefrom, and mechanism connected with said 30 actuating member for locking said actuating member whenever said set of flexible connections is connected with said driven member.

35 3. In a ship's telegraph, the combination, with a set of flexible connections extending from a transmitting station to a receiving station and movable for the purpose of transmitting signals, of actuating mechanism located 40 at the transmitting station and normally disconnected from said flexible connections, mechanism located at the transmitting station and controllable at the will of an operator at the transmitting station, for connecting said actuating mechanism with said flexible connections in order to move said flexible connections in sending a signal to the receiving station, indicating mechanism located at the transmitting station and normally 45 connected with said flexible connections so as to be capable of being operated by movements of the flexible connections, and mechanism located at the receiving station and normally connected with said flexible connections for the purpose of enabling 50 the operator at the receiving station to actuate the flexible connections and thus cause the latter to actuate the indicating mechanism at the transmitting station.

4. In a ship's telegraph the combination, 60 with a single set of flexible connections extending from a transmitting station to a receiving station and movable for the purpose of transmitting signals, of an actuating device located at the transmitting station for 65 the purpose of actuating said flexible connections in order to transmit a signal to the receiving station, an indicating device located at the transmitting station, an indicating device located at the receiving station 70 and normally connected with said flexible connections, an actuating device located at the receiving station and normally disconnected from said flexible connections, and mechanism located at the receiving station 75 for connecting the actuating mechanism of the receiving station with said flexible connections and for disconnecting said indicating device at the receiving station from said flexible connections.

5. In a ship's telegraph the combination, with a set of flexible connections extending between two stations and movable for the purpose of transmitting signals, of a revolute shaft located at each station and adapted 85 to coat with said set of flexible connections in order to drive flexible connections and be driven thereby, a manually operated arm located at each station, a movable pointer located at each station, for the purpose of 90 registering indications, and mechanism located at each of said stations and including a manually operated shifting lever for alternately placing the revolute shaft at that station under control of the manually operated arm at that station, and placing the movable pointer at that station under control of said last mentioned revolute shaft.

6. In a ship's telegraph the combination, 95 with a set of flexible connections extending from one station to another, and movable for the purpose of transmitting signals, of a revolute driving member located at each station and normally disconnected from said flexible connections but capable of being operatively connected with said set of flexible connections in order to drive the same, an indicating member located at each station and capable of being actuated by said flexible connections, and a shifting gear mechanism 100 at each station and controllable at the will of the operator at such station for shifting the connection from said set of flexible connections in order to connect alternately therewith said manually operated arm and said 105 movable pointer.

CHARLES J. HENSCHEL.
